UNITED STATES PATENT OFFICE

JOHN P. CRONIN, OF PATERSON, NEW JERSEY.

CREEL.

1,016,403.

Specification of Letters Patent.

Patented Feb. 6, 1912.

Application filed July 24, 1911. Serial No. 640,071.

To all whom it may concern:

Be it known that I, JOHN P. CRONIN, a citizen of the United States, residing at Paterson, in the county of Passaic and State of New Jersey, have invented certain new and useful Improvements in Creels, of which the following is a specification.

The invention relates to creels for supporting the spools from which the threads 10 are supplied to a warping machine in the operation of preparing warps for looms, and it consists in certain improvements in such apparatus designed to effect a relative movement between the threads and the reed 15 of the creel with a view to prevent the threads wearing nicks or grooves in the reed dents.

At present the relative movement referred to is obtained either through a transmission mechanism connecting the movable reed of the creel with some moving part of the warping machine or by manually operating a crank or similar device from time to time. Both of these expedients are unreliable: the first because, inasmuch as the creel has to be advanced step by step transversely of the warping machine in the laying on of the successive sections of warp, it is practically impossible to provide a reliable transmission mechanism for effecting the movements of the reed associated, as said mechanism must be, with an apparatus (the creel) which, being portable, is not always the same distance from the warping machine; 30 and the second, because the attendant frequently forgets to operate it.

Referring to my invention, the part to be moved to effect the relative movement between the reed and warp threads is connected by suitable transmission mechanism with a roller or rollers serving to support the creel. Inasmuch as, therefore, the creel must be moved transversely of the warping machine at definite intervals in the operation of warping, when such movement occurs the roller referred to rotates and transmits movement to the part to be moved; in this way the movement is accomplished with certainty at definite intervals.

50 In the accompanying drawings, Figure 1 is a side elevation of a creel provided with my improvement; Fig. 2 is a rear elevation of the said creel; and, Fig. 3 is a front elevation showing a detail of the invention.

55 *a* is a creel of usual construction provided with skewers *b* to receive the spools *c*

from which the warp threads are taken in the operation of warping. The creel is supported on rollers *d* all journaled on fixed parallel axes. On the top of the horizontal bar *e* at the upper part of the creel, and suitably secured to the top face thereof, are the brackets *f*. Each bracket includes an upstanding arm *g* formed with a loop *h*, and, back of said arm, an upstanding fork *i*. The brackets are so disposed on the bar *e* that the several loops *h* and forks *i* are aligned with each other. The loops *h* support the usual glass bar *j* over which the threads *A* extend on their way from the spools to the warping machine. The several forks receive and form guides for the reed *k* which is vertically movable therein, although it is held against lateral or endwise movement by the stops *l* abutting against relatively opposite sides of the brackets *f* (Fig. 2). The two rollers *d* at the back of the creel are connected by a connecting rod *m*, its ends being attached to suitable pivots *n* on the rollers.

o denotes parallel pitmen pivotally connecting the rod *m* and the reed, the ends of said pitmen being attached to suitable pivoting devices *p* and *q* on the reed and rod *m*, respectively.

In view of the foregoing it will be seen that each time the creel is moved motion is transmitted from the rollers *d* to the reed, so that the position thereof relatively to the threads *A* is constantly undergoing change; that, moreover, by the employment of the connecting rods and the parallel pitmen, the reed is kept at all times true, that is perfectly horizontal.

Having thus fully described my invention, what I claim as new and desire to secure by Letters Patent is:—

1. In combination, with a creel and a supporting roller thereof, a reed member and a thread supporting member arranged in the creel and one being movable therein substantially in the direction of the length of the reed dents, and means, connecting said movable member with the roller, for transmitting movement to the movable member from the roller upon movement of the creel, substantially as described.

2. In combination, with a creel and two supporting rollers therefor, a reed member and a thread supporting member arranged in the creel and one being movable therein substantially in the direction of the length

of the reed dents, a connecting rod pivotally connecting said rollers, and a plurality of pitmen pivotally connecting the connecting rod and said movable member, substantially as described.

3. In combination, with a creel and a supporting roller thereof, a plurality of brackets carried by the creel and having apertured upstanding arms alined with each other and upstanding forks also alined with each other, a guide-bar received in the aper-

tures of said arms, a reed vertically movable in said forks, and means, connecting the reed with the roller, for transmitting movement to the reed from the roller upon movement of the creel, substantially as described. 15

In testimony whereof I affix my signature in presence of two witnesses.

JOHN P. CRONIN.

Witnesses:
